UNITED STATES PATENT OFFICE.

ERNEST FOX NICHOLS, OF CLEVELAND, OHIO, ASSIGNOR OF ONE-FOURTH TO PAUL A. BLAIR, OF WASHINGTON, DISTRICT OF COLUMBIA; KATHARINE W. NICHOLS EXECUTRIX OF THE SAID ERNEST FOX NICHOLS, DECEASED.

TRAIN-CONTROL SYSTEM.

Application filed April 29, 1921. Serial No. 465,615.

This invention relates to improvements in automatic train control systems with reference more especially to systems of the above character in which the speed of the train and the relative positions of the block signals, as well as the rate of movement of the train relative to the signals, are controlled.

One of the objects of the present invention is to provide a simple, reliable, practical and efficient automatic train control system of the above general character which may be installed at a minimum expense and in which a large part of the apparatus ordinarily in use and operation may be utilized without extensive alterations.

A further object is to provide an automatic electro-magnetic control system and associated train carried parts that will operate regardless of the speed of the train and so positioned and arranged as to permit the operation regardless of whether the engine is backing or going forward.

A further object is to provide a system of the above general character which will be unaffected by weather conditions or dust and dirt or snow and ice as so frequently occurs in railway systems now in use.

A further object is to provide efficient apparatus of the above general character which will operate without mechanical contact between the track side mechanism and the train carried mechanism.

Other objects will be in part obvious and in part hereinafter pointed out.

It is known that there are locomotives now equipped with types of automatic control which, when actuated mechanically, operate in one position to apply the brakes and in another position to operate the brake and also to cut off the steam to the engine, or equivalent motive means, thus bringing the train to a stop. By means disclosed in the present invention, however, such operations are performed automatically without mechanical contact.

The present invention does not comprehend any broad type of train carrying control mechanism, but it deals in the special application herein described, with magnetically operated track side signalling mechanism and with associated magnetically oper-

ated circuit breaking and circuit closing mechanism attached to the train and adjusted to actuate the train control mechanism carried by the engine. But the invention is by no means limited in its use to the receiving of signals or the operation of auxiliary apparatus in regulating the speed of a moving train, car, or carriage from purposely set and operated magnetic bodies along the track or roadway of such moving vehicles. In using the term engine, it is to be understood that either electric or steam engine is comprehended as well as electrically operated motor cars and other train, car, or carrier propelling device or mechanism and in the claims wherein the term engine is used, this term is to be given the appropriate interpretation.

In order that a clearer perception may be had of the present invention, drawings have been appended and form a part of this disclosure, wherein similar reference characters denote corresponding parts throughout the several views.

In the accompanying drawings,—

Figure 1 is a diagrammatic view of that part of the device attached to the train which is adapted to open or close a circuit as it passes relatively to the setting of the track side mechanism, thereby to actuate the speed control and air brake mechanism carried by the engine;

Figure 2 is a vertical sectional view showing the mounting of the elements shown in Figure 1;

Figure 3 is a diagrammatic view showing sections of four blocks of track and the associated track side signalling and speed controlling mechanisms;

Figure 4 is a diagrammatic view showing the track side magnet device; and

Figure 5 is a cross section through s—s of Figure 4.

Referring now to Figure 1, wherein is shown the arrangement and wiring of the magnetic relay parts 1, 2 and 28, which correspond to those parts similarly designated in Figure 2, the part 1 is a non-magnetic metallic plate in which a magnetic needle is mounted in a suitable bearing as at O. This magnetic needle NS is carefully balanced by

inertia near its middle point so that when mounted by process of trial of error in the bearing, tapping or jarring of the frame 1, at any point, or in any direction, will not 5 cause the needle to rotate about its axis. Two knife edged contacts at c , c' are attached to, but insulated from, the plate 1. Into borings in the plate 1 are driven two retentive members such as small short iron 10 rods a and a' . The portion of these rods projecting above the surface of plate 1 may have various forms depending upon the use for which the device is employed and the weakness or strength of the magnetic forces 15 to which the device is intended to respond. The magnetic needle NS is heavily plated with gold, platinum or other good contact-making material. The contacts c , c' are placed in such relation to NS that when NS 20 is in a nearly horizontal position it will make a good electrical contact with c and, when in an inclined position, will make a good electrical contact with c' .

The function of the two soft iron rods 25 a and a' is to hold the needle against the knife edge contact at c , which is so adjusted that the poles of the needle NS come very close to a and a' , but do not actually touch them. The size and form of the retentive 30 members a , a' are so chosen that their attraction will hold the needle in contact at c against the deflecting force of the vertical component of the earth's magnetic force and against small magnetic and mechanical 35 disturbances. They are, however, so chosen in position and size and form that the magnetic impulse to which the device is intended to respond will pull the needle away from them, thus breaking the contact at c . The 40 character of the attracting forces of the retentive members at a and a' for the needle are controlling only when the poles of the needle are close to the armatures and they loose sensible influence upon the needle as 45 soon as the needle has been rotated through a moderate angle. Hence, a magnetic deflecting force of extremely short duration, due to magnetic road side devices, passed at high speed will deflect the needle by a 50 sufficient angle to remove it from the sphere of attraction of a and a' , and the vertical component of the earth's magnetic field will then draw the needle down until its progress is arrested by the knife edge contact c' . 55 The influence of the soft iron retentive members on the needles may be altered and varied by changing their form as well as their positions. In addition to the simple straight rod shown in Figure 1, I may bend 60 the rod in the form of a right angle so that the portion in front of the plate 1 and in the plane of the needle may have the form of a short arm a shown in dotted lines, Fig. 1. This will enable the bent rod at a fixed 65 distance from the needle to exert a firmer

hold upon it than the form of retentive members in Figure 1, and by rotating these arms between horizontal and vertical positions, varying degrees of control can be obtained. 70

Part 28, Figure 1, is a horizontal coil of wire completely surrounding the needle and its mounting. When battery terminals are connected to 3 and 7, a current is sent through coil 28 creating a magnetic field 75 which will independently operate the device, so that if 5-6 be an open circuit and the current sent in one direction through the coil, this circuit can be closed by the magnetic action of the coil current. Likewise circuit 80 4-5 may be opened or closed by sending a sufficient current through coil 28 in one or the other direction.

Figure 2 is a median or central vertical section of the complete mounting of the device shown in Figure 1, as arranged for attachment to a moving train. A casing of bronze or other non-magnetic material 16, is closed by a hinged door parallel to and in front of the plane of the section shown. This bronze casing is divided into an upper and lower compartment by a horizontal partition, 17, and is provided with ears, 21, shown attached to horizontal steel bars, 22, by bolts and nuts, 24 and 23, respectively. These steel bars are preferably attached to the rear truck of a locomotive tender and extend outward to a point 16 to 20 inches from the rail over the tie ends. This position on the tender is preferred because it is further outside the magnetic influence of the more massive steel parts of the locomotive. This device is duplicated in a similar position on the other side of the train, the 95 device on one side of the train being connected to operate the brakes and that on the other side to operate the automatic speed control mechanism carried by the engine. 100

The plate 2 to which plate 1 is attached is secured to a cover plate, 19, which serves as the lid of a glass vessel, 27, and a gasket, 26, is positioned between 19 and the ground rim of 27. On plate 19 is soldered a small brass receptacle, 29, enclosing a hollow space, 31. There is a small opening 12 in the bottom of this receptacle which connects the opening 31, with the chamber in jar 27. The part 29 is closed at the top by a screw, 8, through which is bored a capillary opening, 13, funnelled at the top as shown. To prevent moisture and dust from getting into the bearings of the device and at the same time to serve the purposes of uniform lubrication, the glass jar 27 and the space 31 are completely filled with kerosene or other suitable emulsion liquid. This liquid also, in a measure, prevents sudden jars or shocks from loosening the hold of the armatures a , a' upon the magnetic needle NS. Opening 12 is funnelled to allow any small air 115 120 125 130

bubbles which form in the liquid to escape into the upper box 31, and the small capillary 13 in the screw 8 is for the purpose of equalizing pressure inside and outside the box 31 which holds enough liquid to allow for the temperature contraction and expansion of the liquid in 27. Also, any loss by slow evaporation can from time to time be replaced through this same opening. The glass jar is embedded in a massive lead block, 20, held together by a massive lead back, but the front is left open for a more convenient inspection of the device. Into the top of this lead block two brass bushings, 10, are screwed and into these bushings again are threaded brass rods, 11. The axes of these rods lie in the same vertical plane as the center of gravity of the lead block and parts attached thereto. A brass strip, 9, fitting over these rods is pressed down upon the top of the receptacle 29 by nuts, 14, thereby to compress the gasket 26 and make a liquid tight joint. Through the horizontal partition 17 are holes, 18, considerably larger than the rods 11. In these holes, projecting rims, 30, are attached, and, fitting over the lower projection of these rims and again over the outside of the nuts 14 are two coiled springs 15. Likewise above the partition 17 are corresponding springs 15, held in place at the top by lock-nuts, providing a simple and practical shock absorber for the suspended mechanism.

To further eliminate shocks, the lead block is supported in a soft rubber cushion, so that if the housing 16, for instance, receives a sudden shock, the inertia of the lead block tends to hold it in place and the jar is taken up by the springs. Again, oscillatory motions resulting from jolts would be rapidly damped out by the rubber cushions, 25. The more violent shocks which occur in train operation are mainly either up and down, due to rail joints or unevenness in the track, or are forward and backward, due to starting and stopping the train and to "bumping." A lighter rubber cushion, not shown, is inserted between the back of the lead block 20 and the housing 16, and a similar rubber cushion, mounted on the inside of the door, is provided to press against the lead block when the door is closed. Forward and backward shocks may be further checked if necessary by horizontal coiled springs inserted between the ends of the lead block 20 and the front and back vertical walls of the housing 16. The axes of all springs lie in the vertical plane which contains the center of gravity of the lead block and all parts attached thereto. This is to prevent sudden shocks from producing any rotation of the block 20.

Figure 4 shows a longitudinal section, in which NS is a permanently magnetized steel bar or bundle of bars. C represents coils of

copper wire arranged around the permanent magnet forming a nest, as shown in Figure 5, which represents a cross section at s-s, near the top of Figure 4.

If contact is made by closing the battery circuit by the key at K, Figure 4, or otherwise, an electrical current may be sent through the coils from battery B in such direction and of such intensity, governed by the coil resistance and voltage or by an auxiliary variable resistance R, that the total magnetic effect of the permanent magnet NS upon a magnetic object at a short distance from its pole may be reduced to zero, that is, the pole strength and external field of the magnet, is neutralized or diverted. By reversing the direction of the current, the external field may be correspondingly increased. The current in Figure 4 is sent through the coils C in such direction as to make each coil a magnet with poles opposite in sign to the poles of the permanent magnet. Thus, as indicated in the figure, the north pole of the permanent magnet is at the top and the south pole at the bottom, but the south poles of the coils are at the top and the north poles at the bottom, as indicated by the dotted letters N and S, the dotted lines about the two ends of the system representing magnetic lines of force. At the top these lines of force issue from the north pole of the permanent magnet and are immediately drawn into the coils C, while at the bottom lines of force issue from the coils C and are drawn into the south pole of the permanent magnet. The coils energized by a current as here shown act in a way similar to the soft iron bars or "keepers" used on permanent magnets to gather in the external field of a magnet and delay the loss of its strength by age.

While these coils have effect of neutralizing the external magnetic field of the permanent magnet, they do more than mere keepers and tend to magnetize the permanent magnet more strongly. Thus the magnetic influence of the permanent magnet can be reduced without weakening its permanent magnetization. Ordinarily when it is desired to weaken temporarily the strength of the permanent magnet by means of a coil carrying current, the wire is wrapped directly around the magnet, forming a coil with the magnet at its axis, and if an electric current be sent through such a coil in a direction to weaken the external field of the permanent magnet, the effect of the magnetic field of the coil is in such direction as to demagnetize the permanent magnet or weaken it permanently. Furthermore, the magnetization of a permanent magnet tends to become weaker with time and this method of wrapping the coil carrying current directly around the per-

manent magnet very much hastens this weakening process even to a point where the permanent magnet might become practically demagnetized with one application 5 of the current.

Such a device, therefore, cannot be relied upon to operate in a durable and trustworthy manner, whereas the form herein disclosed, namely, a nest of coils arranged as shown 10 around the permanent bar magnet, tends to strengthen the permanent magnetization of the bar and thus to arrest the aging process referred to above.

There are many possible uses for the combination of permanent magnet and wire coils herein disclosed, but for purposes of illustration rather than limitation, the combination is herein described in its application to a system for transmitting signals from the 15 roadside to a moving railway train.

For the operation of this system, magnetically responsive devices of the character illustrated by Figures 1 and 2 are carried on the moving train and magnets of the type 20 illustrated by Figure 4, connected to batteries by selected control means illustrated by Figure 3 are placed at intervals along the roadway. If no current flows through the magnet coils, the permanent magnets will 25 act upon the magnetically responsive devices on the train and transmit a signal and automatically operate auxiliary mechanisms for speed control or for applying brakes to the train or for operating signals in the engine 30 cab. None of these three last named types of mechanism are, however, any part of this invention. If no speed control is to be exercised or brake applied, a current of such 35 magnitude and direction is sent through the nest of coils as will neutralize the field of the permanent magnet at the shortest passing distance between it and the magnetically responsive device carried by the train. In this case, the train will pass without incident.

Two of the devices illustrated by Figure 2 are carried by the train. One of these, mounted on the right rear truck of the locomotive tender, is put in electrical connection with a speed control device, which 40 specifically is no part of this invention except as it enters into the complete construction, the other, mounted on the left rear truck, is electrically connected to an auxiliary mechanism operating the air brakes. The 45 magnetic units shown in Figure 3, embodying the magnet and coil devices, are so disposed that the herein disclosed devices carried by the train will pass directly over them and within the space necessary to respond to their magnetic influence, that is say 4 to 6 inches.

For an understanding of the operation of the roadside or track side mechanism, reference is here made to Figure 3. The horizontal dotted lines, 32 and 33, indicate the

left and right rails of one track of a double track railroad. It is to be understood, however, that the device can also be adapted to operate on a single track railroad. The sections of the track, E, F, G, H, represent 50 the ends of four consecutive blocks of track.

The parts E', F', G', are signal semaphores operating automatically on the well known block signal system. The parts 34, 35, 36 and 37 shown schematically are permanent 55 magnet units employed at the end of one block to operate speed control or brakes on approaching the beginning of the following block.

These magnetic units consist of the hereinbefore described permanent magnets surrounded by electric coils, the coils being operated by a battery which may be the same battery used to operate the block signal semaphores. In the system which is 60 here being described, the current in the coils surrounding the permanent magnets is used simply to neutralize the effect of the permanent magnets, not to increase it. The potential from the battery 38 is applied through

the dial commutators 39 to the electric coils 65 nested about the permanent bar magnets at 34, 35, 36 and 37. This type of dial commutator consists of two conducting bars 40 and 41 attached at right angles to, and insulated from, each other and rotating about 70

an axis 42. Bar 40 is in constant sliding contact with a copper semi-circle 43 permanently connected to, say, the negative pole of the battery 38. Bar 41 is in similar 75 constant sliding contact with copper semi-circle 44, which is permanently attached to the other pole of the battery. In a semi-circular arrangement are located equally spaced contacts 45, 46, 47, 48 and 49, which are 80 brought into selective connection with the battery terminals by the rotating bars 40 and 41. The dial commutators thus described can be operated by the same mechanism that operates the automatic block signal 85

semaphores or they can be operated by wholly independent circuits of similar character, if desired.

If the dial commutator 39 is set as shown, the two permanent magnets 36 and 37 of that unit, having their south poles up, will be 90 neutralized by the current from the battery through the dial commutator in the wiring scheme shown. Neutralization of these two magnets is indicated by leaving the circles which represent them blank. Now, when 95 the device carried by the train is operating as a closed circuit relay, as in circuit 5-6, Figure 1, it requires the south pole of a magnet below it to break the circuit. The north pole of a magnet below it not only will 100 not break the circuit but, if the circuit be already broken, the north pole of the magnet below it will close the circuit. Similarly, 105 when the device carried by the train is operating as an open circuit relay, as in circuit 110

115

120

125

130

cuit 4—5, Fig. 1, a reverse polarity of the magnet below the device, that is, a north pole of a magnet, is required to break the circuit. This automatic closing of circuit 5—6 is convenient and useful when the train passes out of the block under speed control on to a clear block. Therefore, in the case shown at unit E, the south pole magnets, being neutralized, will not break the circuit of the train device. Thus, if a train approaches in the direction indicated by the arrow, upon coming in view of the semaphore of that unit, clear way will be indicated and the train will pass freely out of block E into block F having a clear signal and the speed control and brake devices held in their normal positions.

The dial commutator 39' shows the connections which will let the train pass from block F to block G without any effect on the brakes, but which will break the circuit of the speed control device on the right side of the train by leaving unneutralized the permanent magnet pole S—37. Thus, when the train approaches the end of block F, before entering block G, the semaphore shows "caution" and the train cannot proceed along the block G at a greater speed than that predetermined by the special speed control mechanism.

The dial commutator 39'' indicates the connections by which the north permanent magnet poles on both sides of the track are neutralized and the corresponding south poles unneutralized. Therefore, to the speed control device which was previously in operation is added the brake device and as the train approaches the end of block G, before entering block H, the semaphore shows "stop" and the train is brought to a stop.

After brakes have been applied, in order to start the train, it will be necessary to press an electric contact 50 which will send a current through the coil 28, Figure 1, and thereby "recock" the brake control device. This "recocking" is effected through a key closing circuit 51 between the terminals 3 and 7, in which circuit is connected the auxilliary battery 52. The completed circuit 5—6 includes a relay battery 53 adapted to energize a coil 54 which controls an armature 55, to open a brake or speed control circuit 56, shown schematically in Fig. 1. The closing of this relay breaks the circuit 56 controlling a speed reducing device in the engine cab, as, for instance, a brake system on the engine, or a regulation of the steam control thereof. When the relay battery 53 is connected with the terminals 4—5, this circuit acts as a circuit closer for the brake or speed control circuit 56, for the coil 54 is then energized to urge the armature 55 in the opposite direction to complete the circuit 56. When the brake

control device has been "recocked", the speed control device remains operative throughout block H unless it is also "recocked". Recocking keys may be located either in the engine cab or at a point where the engineer will have to descend from his cab to the trackside to operate them. If the engineer heeds the semaphore signal G' and stops before reaching the magnets S—36 and S—37, and waits for a caution signal, the automatic speed control will go into operation, or in this case will continue in operation for the block H. Again, if semaphore G' goes from "stop" to "clear", the train will be left wholly in the engineer's hands and he can proceed at full speed.

When a train is drawn by a backing engine, the speed control mechanism carried by the tender can be connected to the brakes by the operation of a reversing switch and likewise, the device used for operating the brakes in forward travel can be thrown over to speed control by the reversing switch, so that the system will operate as before.

Permanent magnets are shown as the nucleus of the trackside units for the reason that if the battery supplying coil currents should fail, its failure could not cause an accident, but would simply cause the train device to throw on the brakes and bring the train to rest. This is the type of precaution which is followed in the automatic block signal system whereby, if the mechanism operating the semaphore fails, the semaphore always shows "stop". For the same reason the magnetic relay, Figure 1, is operated on a closed circuit, 5—6, containing a battery and armature 55 which operates speed control or brakes. Thus, whenever the circuit 5—6 is broken or the battery contained in it fails in potential, speed control and brakes go on automatically.

It is believed that a description of the operation of the general system will be unnecessary in view of the full and complete disclosure above. The invention as a whole is admirably adapted for the purpose for which it is intended inasmuch as it is compact, reliable and efficient for use and operations and designed to accomplish among others all of the objects and advantages set forth herein.

Having thus described my invention, what I claim is:

1. In a system of the character described, in combination, a member adapted to be carried by an engine including a magnetic needle, contacts adapted to be engaged by said needle and retentive members associated with the needle, said retentive members comprising soft iron core members disposed alternately and adjacent the ends

of said needle and adapted by their inherent attraction to maintain the magnetic needle in a normally fixed position, to engage one of said contacts, against the 5 earth's magnetic force, which tends to rotate said needle away from said normally fixed position.

2. In a system of the character described, in combination, a support, a needle adapted 10 to swing in a vertical bearing mounted on said support, retentive members on the support disposed alternately of the needle and in close proximity to which said needle moves as it swings about its axis, said retentive members comprising soft iron cores adapted by their inherent attraction to maintain said needle in a normally fixed position against the earth's magnetic force, a contact engaged by said needle when in 15 said normally fixed position and a contact adapted to be engaged by said needle when the needle swings from its normally fixed position.

3. In a system of the character described, 25 in combination, a support, a needle adapted to swing in a vertical bearing mounted on said support, contacts adapted to be engaged by said needle, retentive members on the support in close proximity to which said 30 needle moves as it swings about its axis, and a coil associated with said needle and its support adapted to move the needle from one position to another when said coil is energized by an electric current in the appropriate direction.

4. In a system of the character described, in combination, a support, a needle adapted 40 to swing in a vertical bearing mounted on said support, contacts adapted to be engaged by said needle, retentive members on the support in close proximity to which said needle moves as it swings about its axis, a coil associated with said needle and its support adapted to move the needle from one 45 position to another when said coil is energized, by a current of appropriate polarity, and a casing of substantially shock-proof construction in which said needle is mounted.

5. In a system of the character described, 55 in combination, a support, a needle adapted to swing in a vertical bearing mounted on said support, contacts adapted to be engaged by said needle, retentive members on the support in close proximity to which said needle moves as it swings about its axis, a coil associated with said needle and its support adapted to move the needle from one 60 position to another when said coil is energized by a current of appropriate direction, a casing of substantially shock-proof construction in which said needle is mounted, and means for securing said casing to an engine or other part of train.

6. In a system of the character described,

in combination, a support, a needle adapted to swing in a vertical bearing mounted on said support, contacts adapted to be engaged by said needle, retentive members on the support in close proximity to which said needle moves as it swings about its axis, a coil associated with said needle and its support adapted to move the needle from one position to another when said coil is energized by a current of appropriate direction, 70 a casing of substantially shock-proof construction in which said needle is mounted, means for securing said casing to an engine or other part of train and a track side mechanism adapted to move said magnetic needle under certain conditions as the same passes over said track side mechanism.

7. In a system of the character described, in combination, a support, a needle adapted to swing in a vertical bearing mounted on said support, contacts adapted to be engaged by said needle, retentive members on the support in close proximity to which said needle moves as it swings about its axis, a 80 coil associated with said needle and its support adapted to move the needle from one position to another when said coil is energized by a current of appropriate direction, a casing of substantially shock-proof construction to which said needle is mounted, means for securing said casing to an engine, a track side mechanism adapted to move said magnetic needle under certain conditions as the same passes over said track side mechanism, and means for varying the 85 external field of said track side mechanism.

8. In a system of the character described, in combination, a train carried member comprising a magnetic needle adapted to swing 90 in a vertical plane, retentive members in close proximity thereto, comprising core members which by their inherent attraction maintain the needle in a normally fixed position against the earth's magnetic force which tends to urge the needle away from said normally fixed position, contacts and circuits associated therewith adapted to be closed or broken as said needle moves from one position to another, and an auxiliary circuit adapted to be energized on the opening and closing of said first named circuits.

9. In a system of the character described, in combination, a train carried member comprising a magnetic needle adapted to swing 105 in a vertical plane, retentive members in close proximity thereto, comprising core members which by their inherent attraction maintain the needle in a normally fixed position against the earth's magnetic force which tends to urge the needle away from said normally fixed position, contacts and circuits associated therewith adapted to be closed or broken as said needle moves from one position to another, an auxiliary circuit adapted to be energized on the opening 110

115

120

125

130

- and closing of said first named circuits, and a track side mechanism adapted to actuate said needle as the same passes thereover.
10. In a system of the character described, 5 in combination, a train carried member comprising a magnetic needle adapted to swing in a vertical plane, contacts and circuits associated therewith adapted to be closed or broken as said needle moves from one position to another, auxiliary circuits adapted to be energized on the opening and closing of said first named circuits, a track side mechanism adapted to actuate said needle as the same passes thereover, said track side 15 mechanism comprising a permanent magnet, a nest of coils grouped about said magnet, and means to energize said coils whereby the external field of said magnet may be neutralized.
- 20 11. In a system of the character described, the combination of a track side mechanism comprising a permanent magnet and means associated therewith for neutralizing the polarity of said magnet, said means comprising a plurality of current-carrying coils grouped about said magnet, said coils adapted to be energized at will.
- 25 12. In a system of the character described, the combination of a track side mechanism comprising a permanent magnet, and means to neutralize the external field of said magnet as desired, said means comprising a plurality of current carrying coils grouped about said magnet and means to energize 30 said coils at will.
- 35 13. In an apparatus of the character described, in combination, a casing adapted to be carried by an engine, a second casing mounted therein, means supporting one from the other whereby shocks are damped before reaching the inner casing, a magnetic needle within said inner casing, adapted to swing in a vertical plane, and contacts associated with said needle together with circuits whereby the circuits are opened and closed as the needle swings from one position to another.
- 40 14. In an apparatus of the character described, in combination, a casing adapted to be carried by an engine, a second casing mounted therein, means supporting one from the other whereby shocks are damped before reaching the inner casing, a magnetic needle within said inner casing, adapted to swing in a vertical plane, contacts associated with said needle together with circuits whereby the circuits are opened and closed as the needle swings from one position to another, and a dampening fluid within 45 which said needle is immersed.
- 50 15. In an apparatus of the character described, in combination, a casing adapted to be carried by an engine, a second casing mounted therein, means supporting one from the other whereby shocks are damped before reaching the inner casing, a magnetic needle within said inner casing, adapted to swing in a vertical plane, contacts associated with said needle together with circuits whereby the circuits are opened and closed as the needle swings from one position to another, and a dampening fluid within 55 which said needle is immersed.
- 60 16. In an apparatus of the character described, in combination, a casing adapted to be carried by an engine, a second casing mounted therein, means supporting one from the other whereby shocks are damped before reaching the inner casing, a magnetic needle within said inner casing, adapted to swing in a vertical plane, contacts associated with said needle together with circuits whereby the circuits are opened and closed as the needle swings from one position to another, a dampening fluid within which said needle is immersed, and a track side mechanism adapted to actuate said needle.
- 65 17. In an apparatus of the character described, in combination, a casing adapted to be carried by an engine, a second casing mounted therein, means supporting one from the other whereby shocks are damped before reaching the inner casing, a magnetic needle within said inner casing, adapted to swing in a vertical plane, contacts associated with said needle together with circuits, whereby the circuits are opened and closed as the needle swings from one position to another, a dampening fluid within which said needle is immersed, a track side mechanism adapted to actuate said needle, said track side mechanism comprising a magnet, and means associated therewith whereby the external field of said magnet may be neutralized thereby to affect or not affect the needle as it passes thereover.
- 70 18. In a system of the character described, in combination, a plurality of magnets, positioned at opposite sides of the track, a plurality of coils grouped about each of said magnets, circuits connected with said coils, and a battery adapted to energize the coils when connected with circuits, and a selective member adapted to connect various magnets with said battery in a predetermined manner.
- 75 19. In a system of the character described, in combination, a plurality of magnets, positioned at opposite sides of the track, a plurality of coils grouped about each of said

magnets, circuits connected with said coils, and a battery adapted to energize the coils when connected with circuits, a selective member adapted to connect various magnets with said battery in a predetermined manner and mechanisms carried by an engine adapted to pass over said track side magnets, and be affected thereby when said track side magnets are energized in a predetermined manner.

20. In a system of the character described, in combination, a plurality of magnets, positioned at opposite sides of the track, a plurality

of coils grouped about each of said magnets, circuits connected with said coils, means adapted to energize the coils when connected with the circuits, a selective member adapted to connect various magnets with said energizing means in a predetermined manner, and mechanisms, carried by an engine adapted to pass over said track side magnets, and be affected thereby when said track side magnets are energized in said predetermined manner.

ERNEST FOX NICHOLS.
